DROPPER CLOSURE FOR CONTAINERS

John A. Elder, Jr., Plainfield, N. J., assignor to Merck & Co., Inc., Rahway, N. J., a corporation of New Jersey

Application February 11, 1952, Serial No. 271,031

6 Claims. (Cl. 222—208)

This invention relates to containers utilized in the sale of fluids adapted to be dispensed from the container by the use of a dropper, as for example, containers for therapeutic fluids, and fluids of the type requiring sterile packaging. In particular, the invention deals with a device of this type and kind wherein a dropper unit constitutes the stopper or closure for the container, the latter having means for tensionally engaging the bottle in retaining the dropper unit thereon and effecting a seal between the stopper and container, and wherein rupturable means may be provided to secure the container and stopper together in providing a tamper-proof package thereof.

More particularly, the invention deals with a device of the character described wherein the stopper top has means on the undersurface thereof engaging the upper end of the container to establish pressure engagement therewith and effect a seal in normal uses of the device from time to time; and still more particularly, the invention deals with a device of the character defined wherein the stopper is capable of movement into angular position with respect to the container so as to position the end of the dropper tube in a lower corner of the container, facilitating dispensing of substantially all of the container contents.

The novel features of the invention will be best understood from the following description, when taken together with the accompanying drawing, in which certain embodiments of the invention are disclosed and, in which the separate parts are designated by suitable reference characters in each of the views, and in which:

Fig. 1 is a longitudinal, sectional view through a device made according to my invention illustrating the same in the sealed position.

Fig. 2 is a view similar to Fig. 1 showing only part of the construction with the seal band removed and showing a modification.

Fig. 3 is a detailed view of the dropper stopper of Fig. 2 removed and omitting part of the construction, and

Fig. 4 is a diagrammatic view of the device shown in Fig. 1 illustrating a use thereof with part of the construction broken away and in section.

In Figs. 1 and 4 of the drawings, I have shown at 10 a container or bottle, preferably of transparent or translucent material, the bottom of the container having a raised wall 11, side walls of the container adjacent the upper end having a contracted neck 12 outwardly of which is an annular collar or bead 13. The neck and bead constitutes what may be termed an upper, open end portion 14 of the container, and the bore of this end portion has substantially centrally thereof an outwardly extending annular recess 15. At 16 is shown the outer surface of the portion 14, which surface may be termed the top of the container or bottle. At 17, I have shown the combined dropper stopper unit of the device. This unit includes a stopper body 18 having an enlarged, annular band or collar portion 19 and a substantially conical plug or stopper 20. The plug or stopper has at

2

its widest diameter portion an annular bead 21, which is spaced from the band or collar 19 by a short cylindrical portion, and which is adapted to snap into the recess 15 in retaining the unit 17 on the container with the lower surface of the collar portion 19 in pressure engagement with the surface 16. This engagement is facilitated by an annular groove or recess 22 formed in the lower surface of the band 19 at the upper end of the plug or stopper 20. The unit 17 has a bore 23 disposed primarily within the band 19 and plug 20, this bore being enlarged at its lower end as seen at 24, and having an annular recess 25 where the plug 20 joins the band 19. The recess 25 is adapted to receive an outwardly extending bead or flange 26 on a dropper tube 27, this tube projecting below the plug 20 into the container 10 to a point adjacent dome bottom 11 as seen in Fig. 1. The lower end of the tube 27 has a contracted discharge as at 28.

Extending upwardly from the central portion of the band 19, the unit 17 has an elongated bulb 29, bore 30 of which is slightly greater diameter than the bore 23 and joins the bore 23 in a bevelled wall portion 31 at the upper end of the band 19. The entire unit 17 is composed of flexible rubber having sufficient resiliency to provide the sealing and closing effects which are desired, particularly in holding the lower surface of the band 19 firmly upon the surface 16, even after the tear-off ring or strap 32 has been removed. This ring or strap 32 can be of any desired construction, many of such devices being known in the art. It can be in the form of a metallic or other thin wall material, having means for rupturing or tearing the wall portion by hand to facilitate releasing the unit 17 for manual detachment from the container 10 in the unit of the device. In other words, in the sale of the device, the ring 32 constitutes part of the device until the purchaser has removed the same in using the dropper for administering the required amount of drops of the fluid contents of the container 10.

It will be understood that by providing the enlarged diameter 24 of the bore 23, initial attachment of the dropper tube 27 with the stopper is facilitated, and when mounted, it will appear that the tube 27 has a smaller, outside diameter than the diameter of the bore 23 which provides a slight freedom of swinging movement of the tube 27 in the stopper, and this freedom of movement, in addition to the ability to flex the stopper in the manner diagrammatically illustrated in Fig. 4 of the drawings, facilitates positioning the lower end of the tube 27 adjacent a corner 33 of the container 10 when in tilted position, as shown, to facilitate dispensing substantially all of the contents of the bottle or container.

In Figs. 2 and 3 of the drawing, I have shown a slight modification of the construction shown in Figs. 1 and 4 in which 10' represents a container or bottle similar to the container or bottle 10, and 17' represents a dropper stopper unit similar to the unit 17. In these figures, 18' represents a stopper body having a band 19' and a plug or stopper 20', the annular bead of which is indicated at 21', this bead fitting within the recess 15' of the container. At 27' is shown the dropper tube similar to the tube 27, and 29' shows a bulb similar to the bulb 29. The primary difference between the structure shown in Figs. 2 and 3 from that shown in Fig. 1 resides in the provision of a downwardly projecting annular sealing ring 34 on the lower surface of the band 19' outwardly of the recess 22' which is similar to the recess 22. The band 19' also has another recess 35 disposed outwardly of the ring 34, which recess in combination with the recess 22', facilitates flexure of the sealing ring 34 to effect a more positive seal of the unit 17' upon the upper surface 16' of the container in normal uses of the device. In other words, by providing the downwardly extending seal-

ing ring 34 of resilient material it will be apparent that when the bead 21' snaps into the recess 15', the ring 34 will be flattened out or flexed to common alignment with the lower surface 36 of the outer peripheral portion of the band 19' and will be maintained in this flattened pressure engagement with the surface 16' to effect a positive seal.

This latter feature is advantageous when the device is used with certain types and kinds of fluids or medicinal preparations, and the purpose is to minimize displacement of the fluid, particularly when the container is carried about in other than perpendicular positions. This seal is further advantageous from a standpoint of rendering the container airtight to prevent undue evaporation and to prevent contamination of the container contents which might take place with certain types and kinds of fluids or preparations. It will be understood that an effective seal is also established with the structure shown in Figs. 1 and 4 in that the band 19 has a pressure engagement with the surface 16; but as the surfaces are relatively wide, the rounded sealing ring 34 projecting to a slight extent can effect a more positive and sure seal.

In a complete assemblage embodying my novel dropper stopper unit mounted on a container, the inclusion of a rupturable ring or strap, as shown at 32, provides a packing and shipping container which is tamper-proof and which has the further advantage of facilitating sterile packaging of liquids when this is desired. After removal of the rupturable ring or strap, the maintenance of a sterile condition in the residual fluid in the container between intermittent uses thereof is facilitated by the snap engagement between the stopper and container and by the effective seal thereby provided between the container top and band or flange portion of the stopper.

It should also be noted in this connection that the annular groove 22 or 22' permits slight vertical flexure of the entire flange, or band 19, 19' as the stopper is drawn downwardly by engagement of the beaded portion thereof with the annular recess 15, 15' in the container neck. Thus the stopper can adapt itself to slight variations in positioning of the annular recess 15, 15' in the container.

Having fully described my invention, what I claim as new and desire to secure by Letters Patent is:

1. A device of the character described comprising a container having an open end with a contracted neck portion, the contracted neck having an annular groove on the inner surface thereof, a dropper stopper unit mounted on the open end of the container, said unit comprising a stopper part, an outwardly projecting band part and a bulb part, the stopper and band having a bore in alignment with end opening into the bulb part, a dropper tube mounted in said bore and projecting from the unit into the container, the free end of said tube having a contracted discharge, and said stopper part having a projecting bead portion engaging the groove of said neck, a short cylindrical portion above said bead portion, and a conically tapered shank depending from said bead portion, and the lower surface of said band including annular deformable means facilitating vertical displacement thereof in engaging said open end of the container.

2. A stopper unit for containers having an annular groove in the bore of the open end portion of the container, said stopper comprising a stopper part and an integral outwardly projecting band part composed of readily flexible material, said band part being adapted to engage the upper surface of the open end of the container in connection with which the stopper is mounted, the stopper part including an outwardly projecting annular bead adapted to enter the groove in the bore of the container in tensionally supporting said band upon said surface of the container in effecting a seal of the stopper thereon, said stopper part including below said bead a

conically tapered shank portion the lower surface of said band having deformable means providing vertical displacement of said band for effecting a circumferential seal on the surface of the container outwardly and in spaced relation from the stopper part, and said last named means comprising an annular groove in the lower surface of said band adjacent said stopper part.

3. A dropper stopper unit for containers having an annular groove in the bore of the open end portion of the container, said unit comprising a stopper part, an integral outwardly projecting band part composed of readily flexible material, and a flexible bulb part, the stopper part and band having a bore in alignment with and opening into the bulb part, a dropper tube mounted in said bore and projecting from said unit, said band part being adapted to engage the upper surface of the open end of the container in connection with which the stopper is mounted, the stopper part including an outwardly projecting bead adapted to enter the groove in the bore of the container in tensionally supporting said band upon said surface of the container in effecting a seal of the stopper thereon, and the portion of the stopper part below said bead having an essentially conical downwardly tapered contour, and means providing limited swinging movement of the dropper tube with respect to said bore.

4. A dropper stopper unit for containers having an annular groove in the bore of the open end portion of the container, said unit comprising a stopper part, an integral outwardly projecting band part composed of readily flexible material, and a flexible bulb part, the stopper part and band having a bore in alignment with and opening into the bulb part, a dropper tube mounted in said bore and projecting from said unit, said band part being adapted to engage the upper surface of the open end of the container in connection with which the stopper is mounted, the stopper part including an outwardly projecting bead adapted to enter the groove in the bore of the container in tensionally supporting said band upon said surface of the container in effecting a seal of the stopper thereon, and the lower container engaging surface of said band having an upwardly extended annular groove adjacent the stopper part facilitating substantial vertical and angular displacement of said band.

5. A device as defined in claim 1 wherein said deformable means comprises an annular groove in the lower surface of said band adjacent said stopper part providing a weakened portion facilitating vertical displacement of the remainder of said band.

6. A device as defined in claim 1 wherein the outside diameter of said tube is less than the diameter of said bore facilitating lateral movement of the tube with respect to said unit, and said lateral movement of the tube, together with the conically tapered shank of said stopper part, and deformable means on said band permitting orientation of said unit to dispose the lower end of said tube substantially at the bottom periphery of said container.
